[57] CLAIM

The ornamental design for a chair, as shown and described.

DESCRIPTION

FIG. 1 is a side elevational view of a chair showing my design, the opposite side being a mirror image thereof; FIG. 2 is a front elevational view; and, FIG. 3 is a side perspective view thereof. The undisclosed rear surface of the backrest is the same in appearance as the front thereof.

FIG. 1

FIG. 2

FIG. 3
